ABSTRACT OF THE DISCLOSURE

A self-supporting plastic lid for open-head containers, and containers employing such a lid, wherein the lid and container are so constructed as to provide a liquid-tight dust-tight closure at all times when in use, even when the lid is not clamped tightly in place, and wherein the lid is resistant to both deformation forces and aggressive substances while at the same time having no deleterious effect on the stored contents of the container.

BACKGROUND OF THE INVENTION

The present invention relates to containers and, more particularly, to lids for open-head containers of the type commonly used in transporting and/or storing liquid, semi-liquid, pulverized, granular or other substances. In its principal aspects, the invention is concerned with an improved lid made of self-supporting plastic material characterized by its resistance to both deformation forces and aggressive substances, and to containers employing such lids, wherein the container and the lid are constructed so as to mutually cooperate with one another to provide an effective liquid-tight dust-tight closure assembly under various conditions of use.

There has been an ever-increasing demand for containers which are suitable for storing and/or transporting a wide range of different types of substances including substances which are, or may become, aggressive to the container itself. Such containers generally have a sidewall formed of a suitable thermoplastic material or of fibrous material. Alternatively, the sidewall may be formed of metal or fiber board and then internally coated or lined with a thermoplastic material.

It has, however, been found that metallic lids for containers of the foregoing types are undesirable, particularly when the substance to be stored in the container is of such a nature that it can attack the lid or be contaminated thereby. In an effort to solve this problem, it has been proposed that lids made of fiber board or the like be employed; but such proposal has not provided an effective solution for the problem since this type of lid normally is incapable of withstanding the normal rigors of usage. Nor has it been found satisfactory to employ the more resistant metallic lids in conjunction with thin flexible sheets of thermoplastic material, the latter serving as a lid liner. Such latter constructions are disadvantageous in that they normally require the use of separate closure components such as the lid itself and the sheet liner. Moreover, problems are created in acquiring an effective seal for such constructions.

Accordingly, it is a general aim of the present invention to overcome the foregoing disadvantages by providing an improved self-supporting plastic lid which can be removably affixed to the open end of an open-head container formed of a wide range of different materials.

It is another object of the invention to provide an improved self-supporting plastic lid for open-head containers, and containers embodying the same, which are char-

2

acterized by their simplicity, ease of assembly, disassembly and reassembly, and which are reliable in use.

A further object of the invention is the provision of containers and self-supporting lids of the foregoing type which are liquid-tight and dust-tight both when completely assembled in tightly closed condition for shipment and when only partially assembled—for example, when the conventional clamping ring used to rigidly affix the lid to the container sidewall is removed. A related object of the invention is the provision of a plastic lid and open-head container construction wherein the lid is of unitary construction and wherein the lid effectively cooperates with the sidewall to form two distinct and circumferentially continuous sealing regions.

Other objects and advantages of the invention will become apparent as the following description proceeds, taken in conjunction with the accompanying drawings in which:

FIGURE 1 is a side elevation of an exemplary open-head container here having its open end closed by a removable closure assembly in accordance with the present invention;

FIG. 2 is an enlarged fragmentary cross-sectional view of a container and plastic lid embodying the features of the present invention, the container being of the type shown in FIG. 1 but here having the conventional expandable and contractable split clamping ring removed, the components being shown in the loosely closed position;

FIG. 3 is a cross-sectional view similar to FIG. 2, but here showing the clamping ring in position with the components in the tightly closed position;

FIGS. 4 and 5 are cross-sectional views similar to FIG. 3 but depicting modified forms of plastic lids also embodying the features of the present invention; and,

FIG. 6 is a cross-sectional view similar to FIG. 2, but depicting yet another modified form of plastic lid embodying the present invention.

While the invention is susceptible of various modifications and alternative forms, specific embodiments thereof have been shown by way of example in the drawings and will herein be described in detail. It should be understood, however, that it is not intended to limit the invention to the particular forms disclosed, but, on the contrary, the intention is to cover all modifications, equivalents and alternatives falling within the spirit and scope of the invention as expressed in the appended claims.

Referring now to the drawings, there is shown in FIG. 1 a container, generally indicated at 10, having a sidewall 11 and upper and lower closure assemblies generally indicated at 12 and 14 respectively. As heretofore indicated, the material from which the sidewall 11 is made is not critical to the present invention, it being understood that the sidewall 11 will either be formed of material that is inert with respect to the substances to be stored in the container, or, alternatively, it will be internally coated, lined or otherwise treated so as to impart such inert characteristic to the sidewall. Thus, the sidewall 11 may be formed of a thermoplastic material, a fibrous material, or even of suitable sheet metal. In the latter case, and even in the case of fibrous materials, the sidewall may be coated with a thermoplastic material (not shown) or otherwise treated to render it impervious and inert. Alternatively, a separate plastic bag-like liner (not shown) may be employed in a conventional manner.

For the purpose of permanently closing the lower end of the container 10, the lower closure assembly 14 includes a bottom member (not shown) which is rigidly and permanently affixed to the sidewall 11 by means of a conventional metallic reinforcing ring 15. The latter is deformed inwardly as indicated at 16 to form an internal rib (not shown) against which the bottom member

is seated, with portions of the bottom member, the sidewall 11 and the ring 15 being curled together to form a bottom chime 18.

In order to permit both the loading of substances into the container 10 and their subsequent complete or partial removal therefrom, the upper closure assembly 12 is both removable and replaceable. To this end, the upper end of the sidewall 11 is reinforced by means of a suitable metallic reinforcing ring 19 which, as best illustrated in FIGS. 2 and 3, is curled about the upper extremity 20 of the sidewall, the ring 19 and sidewall being formed with an external circumferential groove 21 defining a complementary internal circumferential rib 22 adjacent the upper extremity 20 of the container 10. When a lid (not shown in FIG. 1, but indicated generally at 24 in FIGS. 2 and 3) is applied to the upper extremity 20 of the container sidewall 11, it can be removably yet firmly affixed thereto by any suitable clamping means such, for example, as the conventional expandable and contractable split clamping ring 25 shown in FIGS. 1 and 3.

In accordance with one of the important aspects of the present invention, the removable lid 24 or cover is of unitary construction and is formed of self-supporting plastic material, the lid having a first annular skirt which is deformable into the groove 21 in the sidewall 11 for fixedly retaining the lid in place during transportation, and a second annular skirt which is complementary to and cooperates with the internal rib 22 to form a liquid-tight and dust-tight seal. To this end, the plastic lid or cover 24 (FIGS. 2 and 3) is formed of thermoplastic material such as polyethylene. The lid includes a generally flat central portion 26 surrounded by a channel-shaped rim 28. The outer wall of the rim 28 defines the outermost annular skirt 29, while the inner rim wall defines a concentric inner annular skirt 30.

In keeping with the invention, the second or inner skirt 30 is dimensioned so that when the lid 24 is placed on the container extremity 20, the lower-most or free terminal edge 31 of the skirt extends below the rib 22, there being an intermediate skirt portion 32 which is shaped complementary to the rib. The arrangement is such that the complementary portion 32 of the inner skirt 30 has a maximum external diameter D1 (FIG. 2) which is somewhat greater than the minimum internal diameter D2 of the rib 22. Thus, when the lid 24 is placed on the container extremity 20 and a slight downward force is imparted to the lid in an axial direction, the natural resiliency of the skirt 30 is such that the region of largest diameter D1 in the skirt portion 32 is deformed radially inwardly, thereby permitting the skirt 30 to snap over the rib 22. The skirt 30 then resumes its normal unflexed state and the rib 22 and complementary skirt portion 32 thereafter cooperate (a) to tightly engage one another so as to retain the lid 24 firmly yet removably in place and (b) to establish a first circumferential liquid tight and dust-tight seal. Such seal, being in the region of the rib 22, effectively serves to prevent contact between the contents of the container 10 (FIG. 1) and the curled-over portion of the upper metallic reinforcing ring 19. To facilitate assembly of the container body 11 and lid 24, the free edge 31 of the inner skirt 30 flares inwardly, having an outside diameter D3 less than the internal diameter D2 of the rib. This enables the inwardly flaring portion of the skirt to guide the lid 24 into position during assembly.

It will be observed that when the lid 24 and sidewall 11 are in the relative positions shown in FIG. 2, the first or outer annular skirt 29 surrounds the curled over portion of the upper reinforcing ring 19, thus defining a second circumferential liquid-tight and dust-tight seal. Thus even though the split clamping ring 25 is not yet in place, the container 10 may be safely stored in the condition shown in FIG. 2.

For the purpose of further enhancing the liquid-tight and dust-tight integrity of the container 10, particularly

during transportation but not necessarily limited to periods of transportation, the lid 24 may be firmly clamped in place by means of the conventional split clamping ring 25 shown in FIGS. 1 and 3. In keeping with this aspect of the invention, the outer annular skirt 29 includes a depending portion 34 which extends beyond the upper edge of the groove 21. Thus, when the split clamping ring 25 is applied and tightened, the skirt portion 34 is bent from the position shown in FIG. 2 inwardly into the external groove 21 (as shown in FIG. 3) and into intimate surface-to-surface sealing engagement with the metallic reinforcing ring 19 throughout the entire axial length of the skirt 29. This not only serves to increase the sealing area between the skirt 29 and ring 19, and to enhance the seal defined thereby, but, in addition, the lid 24 is now firmly clamped in place on the sidewall 11. Consequently, even should the container be dropped when filled, there is virtually no possibility of the lid 24 being disengaged therefrom.

To further improve the closure and sealing assembly, the free edge of the extending portion 34 of the skirt 29 may be formed with a thickened bead 35. Such bead 35, as best shown in FIG. 3, provides further insurance against the lid 24 slipping from beneath the clamping ring 25 and off the container 10.

In carrying out the present invention in accordance with the form thereof illustrated in FIGS. 2 and 3, the substantially flat central portion 26 of the lid is connected to the inner skirt 30 generally in the region of the portion 32 of the latter which is complementary to the rib 22, as best indicated at 36. This construction is particularly advantageous in that it tends both to rigidify the inner skirt 30 and to press the latter firmly into sealing engagement with the rib 22.

Referring next to FIG. 4, a slightly modified lid, generally indicated at 38, has been shown. The lid 38 is, in most respects, identical to the lid 24 shown in FIGS. 2 and 3. Therefore, identical portions of the lid and of the container are represented by the same reference numerals. However, in this form of the invention it will be observed that the flat central portion 26 of the lid 38 is connected to the channel-shaped rim 28 at the point, generally indicated at 39, most remote from the inwardly flared free edge 31 of the inner skirt 30. This construction is particularly advantageous in that the inner skirt 30 retains its maximum natural resilience, a desirable feature for compensating for possible deviation in diameter of the rib 22 when the latter is not formed to close tolerance.

Yet another modified lid construction also embodying the features of the invention is illustrated in FIG. 5, like portions of the components again being designated by the same reference numerals and unlike portions being designated by different reference numerals. In this exemplary construction the lid, generally indicated at 40, includes a flat central portion 26 which is connected to the skirt 30 in the region of the inwardly tapered free edge 31 of the latter, as best indicated at 41. This construction has the advantage that the free edge 31 of the skirt 30 is supported, thus rigidifying the skirt 30 and pressing the latter firmly into sealing engagement with the rib 22.

To facilitate application of the split clamping ring 25 (shown in FIGS. 1 and 3-5), particularly in those instances where the plastic lid is formed of high density thermoplastic material that tends to preclude bending thereof, provision may be made for increasing the flexibility of the outer annular skirt 29. To accomplish this, and as best illustrated by the lid 42 shown in FIG. 6, a plurality of circumferentially spaced, axially extending slots 44 are formed in the downwardly extending portion 34 of the outer annular skirt 29, the slots defining a plurality of lips or tongues 45. The presence of such slits 44 greatly increases the flexibility of the skirt portion 34, permitting the tongues 45 defining the skirt portion 34

to be bent inwardly upon contraction of the expandible and contractable split clamping ring 25.

Those skilled in the art will appreciate that the width of the slits 44 and tongues 45 is not critical to the present invention, and may vary dependant upon the particular characteristics of the thermoplastic material used to form the lid. Indeed, when the plastic material is relatively flexible, although self-supporting, such slits may not be necessary. Similarly whether the particular lid construction selected conforms to that shown in FIGS. 3, 4, or 5 will depend upon such variable conditions as the material employed for the lid and/or the sidewall, as well as the dimensions or tolerances of the lid and/or sidewall.

I claim as my invention:

1. A container comprising, in combination, a container sidewall, a bottom wall affixed to one end of said sidewall, and a lid removably affixed to the other end of said sidewall; said sidewall having an external circumferentially disposed groove formed therein adjacent its said other end, said groove defining an internal complementary circumferential rib in said sidewall; said lid being of unitary construction and formed of self-supporting plastic material, said lid having a first downwardly extending circumferentially disposed annular skirt dimensioned to extend beyond the upper edge of said groove, said lid having a second annular skirt disposed concentrically within said first skirt, said second skirt having a free terminal edge extending beneath said rib, said second skirt having a portion complementary to the inner surface of said rib with said portion having a maximum external diameter in the region thereof closest to said free edge which exceeds the minimum internal diameter of said rib whereby said lid is retained firmly yet removably in place by virtue of the cooperative engagement of said rib and said second skirt and the natural resiliency of the latter, and said lid having a generally flat central portion joined to an integral with said second skirt.

2. A container as set forth in claim 1 further characterized in that means are provided for clamping said lid in place upon said container, said clamping means having an annular portion extending into said groove for bending the portion of said first skirt extending beyond the upper edge of said groove into said groove and clamping said portion of said first skirt tightly against said sidewall.

3. A container as set forth in claim 2 further characterized in that said portion of said first skirt terminates in an annular thickened bead, said bead being greater in thickness than the space between said sidewall and said annular portion of said clamping means whereby inadvertent withdrawal of the bent-over portion of said first skirt is precluded.

4. A container as set forth in claim 2 further characterized in that said clamping means comprises an expandible and contractable channel-shaped split ring.

5. A container as set forth in claim 1 further characterized in that said lid is formed of a thermoplastic material.

6. A container as set forth in claim 5 further characterized in that said material is polyethylene.

7. A container as set forth in claim 1 further characterized in that said flat central portion of said lid is joined to said second skirt at a point disposed axially outward of the portion of said skirt shaped complementary to said rib so as to maximize the resiliency of said second skirt, said second skirt projecting downwardly from said central lid portion.

8. A container as set forth in claim 1 further characterized in that said flat central portion of said lid is joined to said second skirt in the region defined by the said portion of the latter which is complementary to said rib so as to snugly urge said complementary portion into engagement with said rib.

9. A container as set forth in claim 1 further characterized in that said flat central portion of said lid is joined

to said second skirt at a point adjacent the free edge of the latter so as to maximize the rigidity of the latter.

10. A container as set forth in claim 1 further characterized in that the portion of said first skirt extending beyond the upper edge of said groove is axially slitted at circumferentially spaced points so as to decrease resistance to inward bending thereof into said groove.

11. A plastic lid for use with a container of the type having a sidewall and a bottom wall affixed to one end of the sidewall with the sidewall having an external circumferentially disposed groove formed therein adjacent its other end and defining an internal complementary circumferential rib in the sidewall, said lid characterized in that it is of unitary construction and is formed of self-supporting plastic material, said lid having a first downwardly extending circumferentially disposed annular skirt dimensioned to extend beyond the upper edge of the groove, said lid having a second annular skirt disposed concentrically within said first skirt, said second skirt having a free terminal edge dimensioned to extend beneath the rib, said second skirt having a portion complementary to the inner surface of the rib with said portion having a maximum external diameter in the region thereof closest to said free edge which exceeds the minimum internal diameter of the rib so as to permit said lid to be firmly retained yet removably mounted in place on the container by virtue of cooperative engagement between the rib and said second skirt and the natural resiliency of the latter, and said lid having a generally flat central portion joined to and integral with said second skirt.

12. A plastic lid as set forth in claim 11 further characterized in that said first skirt terminates in a thickened annular bead.

13. A plastic lid as set forth in claim 11 further characterized in that the free edge of said second skirt flares radially inwardly and is of smaller external diameter than the smallest external diameter of the portion of said second skirt which is complementary to the rib.

14. A plastic lid as set forth in claim 11 further characterized in that said lid is formed of thermoplastic material.

15. A plastic lid as set forth in claim 14 further characterized in that said material is polyethylene.

16. A plastic lid as set forth in claim 11 further characterized in that said flat central portion of said lid is joined to said second skirt at a point disposed axially outward of the portion of said skirt shaped complementary to the rib so as to maximize the resiliency of said second skirt, said second skirt projecting downwardly from said central lid portion.

17. A plastic lid as set forth in claim 11 further characterized in that said flat central portion of said lid is joined to said second skirt in the region defined by the said portion of the latter which is complementary to the rib so as to rigidify the said second skirt.

18. A plastic lid as set forth in claim 11 further characterized in that said flat central portion of said lid is joined to said second skirt at a point adjacent the free edge of the latter so as to maximize the rigidity of the latter.

19. A plastic lid as set forth in claim 11 further characterized in that said first skirt has formed therein a plurality of circumferentially spaced axially extending slits for reducing resistance of said skirt to bending forces.
